DESIGN FOR A FLUID PUMP

Martin E. Marsalis, Fort Worth, Tex.

Application January 8, 1947, Serial No. 136,011

Term of patent 14 years

(Cl. D65—1)

To all whom it may concern:

Be it known that I, Martin E. Marsalis, a citizen of the United States of America, residing at Fort Worth, in the county of Tarrant and State of Texas, have invented a new, original, and ornamental Design for a Fluid Pump, of which the following is a specification, reference being had to the accompanying drawing, forming part thereof.

Figure 1 is a side elevational view of a fluid pump embodying my new design.

Figure 2 is a front elevational view thereof, and Figure 3 is a plan view thereof.

I claim:

The ornamental design for a fluid pump, substantially as shown.

MARTIN E. MARSALIS.
